GARMENT HOLDING CLIP

Lee Oliver, New York, N. Y., assignor to The Connecticut Web and Buckle Company, Bridgeport, Conn., a corporation of Connecticut

Application August 20, 1938, Serial No. 225,877

3 Claims. (Cl. 24—258)

This invention relates to new and useful improvements in garment holding clips, and has particular relation to clips of the type to be used for attaching a supporting strap, as the strap of a suspender or the like, to a garment.

An object of the invention is to provide a clip for the purpose indicated and which while suspended from a strap, tape or the like may be easily and quickly applied to an edge portion of a garment, and which will securely grip the garment for the support thereof.

Another object is to provide a clip including a two part construction comprising a clip body and a lever so constructed as to be readily assembled without the use of tools.

Other objects and advantages will become apparent from a consideration of the following detailed description taken in connection with the accompanying drawing wherein a satisfactory embodiment of the invention is shown. However, it is to be understood that the invention is not limited to the details disclosed, but includes all such variations and modifications as fall within the scope of the invention and of the appended claims.

In the drawing:

Fig. 1 is a front elevational view of my improved clip, the same being shown closed and attached to the lower end of one strap of a suspender;

Fig. 2 is an edge elevational view of the parts of Fig. 1;

Fig. 3 is a rear elevational view of such parts;

Fig. 4 is a longitudinal sectional view through the assembly of Fig. 1;

Fig. 5 is a side elevational view of the clip, the same being shown open and the view showing the manner of applying the clip to a garment;

Fig. 6 is a front elevational view showing the blank from which the body of the clip is formed;

Fig. 7 is an edge view of the blank of Fig. 6;

Fig. 8 is a view similar to Fig. 6 but showing the blank partly formed;

Fig. 9 is an edge view of the partly formed blank of Fig. 8;

Fig. 10 is a front elevational view of the clip lever;

Fig. 11 is an edge view of the lever;

Fig. 12 is a bottom plan view of the lever; and

Fig. 13 is an edge elevational view showing the manner in which the clip is assembled.

The clip of the invention includes but two parts, the body 10 and the lever 11. This clip is shown as applied to the lower end of a suspender strap 12, and for the purpose of securing the clip

to the strap the latter has its end portion 13 looped about a bar or connecting portion 14 of the lever 11, and may be provided with any or the usual adjusting slide or buckle 15.

Clip body 10 is formed of a single piece of spring metal, and the blank for such body is shown at 16 in Figs. 6 and 7. The blank includes hook-shaped ears 17 arranged at its edges toward one of its ends. Inwardly of the ears 17 the blank is provided with lateral projections 18, 10 and adjacent its inner end with lateral projections 19 and end projections 20, the purpose of all of which will fully appear.

Figs. 8 and 9 show the partly formed blank, and there it will be noted that the blank has been 15 folded along the dotted lines 21 of Fig. 6 whereby the ears 17 extend forwardly of the body of the blank, and whereby to provide forwardly extending jaw portions 22. The extreme upper end portion of the blank has been bent to extend 20 forwardly providing a jaw portion 23.

An intermediate portion 24 of the blank has been forced rearwardly providing a transverse groove or depression 25, and below such depression the lateral and end projections 19 and 20 25 have been bent to extend forwardly providing jaw or gripping portions designated 26 and 27 respectively. Projections 18 remain in the plane of the body of the blank.

After the blank has been formed up as in Figs. 30 8 and 9, it is bent upon itself whereby to provide the clip body 10, which as shown includes front and rear arms 28 and 29 respectively connected at their upper ends. The body 10 being of spring metal it will be clear that the arms 28 and 29 35 may be forced toward one another whereby to move their jaw portions 30 and 31 (which jaw portions comprise the free end portions of the arms) toward one another and into closed relation.

Normally the arms 28 and 29 tend to spring apart to have the jaws 30 and 31 open. The lever 11 is operable to move the arms toward one another and thereby close the jaws. Lever 11 in addition to the connecting bar 14 includes side arms 32 and 33 which are connected by such portion 14, and a bar 34 connecting the lower ends of the arms 32 and 33.

Bar 34 of the lever projects out of the plane of the lever as clearly shown in Figs. 11 and 12, 50 and includes a tongue-like portion 35 comprising a cam for forcing the clip arms 28 and 29 toward one another as will fully appear. The lever is mounted on the body by means of the hook-like ears 17, and here it is noted that such ears have 55

their open sides toward the body of the clip, and that such ears, while carried by the arm 28, project across the edges of the arm 29.

In assembling the lever on the clip body the 5 arms of the latter are squeezed toward one another, as in Fig. 13, and the jaw portions of the body are passed between the lever arms 32 and 33 with the bar 34 of the lever against the clip body. While the clip arms are being squeezed 10 together the lever bar 34 may be passed into the hook-shaped ears 17 as suggested by the full line showing in the mentioned Fig. 13, and on the arms of the clip body being released they spring apart carrying the lever bar 34 into place 15 as shown in dotted lines.

The parts are then positioned as in Fig. 5 with the lever forwardly of the body and with the jaws 30 and 31 open. Now by a vertical movement of the body it may be disposed with 20 its jaws at opposite sides of the garment, a portion of which is shown at 36, and thereafter the lever 11 is swung rearwardly to position it substantially in the plane of the clip body as shown in Figs. 1 through 4. In such figures the cam 25 portion 35 of the lever is in a position forcing the arm 29 toward the arm 28 of the clip body and therefore the jaws 30 and 31 are closed.

It is to be particularly noted in Fig. 5 that when the clip is released the lever 11 is extending 30 forwardly from the body 10 of the clip and also the body of the wearer of the garment 36. Therefore the clip body 10 can be easily slipped downwardly over the upper edge of the garment while this body and the garment are in a natural vertical position. It is thus not necessary 35 either that the lever 11 be forced backwardly against the body of the wearer of the garment or that the upper edge of the garment be pulled outwardly away from the wearer's body and 40 into an unnatural position in order to slip the clip on over the edge of the garment.

It is noted particularly in Fig. 4 that when the jaws 30 and 31 are closed the cam 35 has entered the depression 25 in the clip arm 29 which 45 will offer a resistance to movement of the cam out of the depression, whereby the lever will not be casually moved or swung relative to the clip body to permit the clip jaws to open. As the jaw 30 includes the forwardly turned portions 22 and 23, and the jaw 31 includes the 50 similar portions 26 and 27, it will be apparent that any material between the jaws will be securely gripped when the jaws are closed. The portion 27 is preferably provided with teeth 20 and the edge 23 may have teeth if desired. Portions 23 and 27 hold the garment against slipping from the clip while the portions 22 and 26 grip the garment to prevent the clip sliding sideways on the garment by a lateral pull on 55 the web 12.

Movement of the lever 11 rearwardly with respect to the body 10, as from the position of Fig. 5 to that of Fig. 2 is limited whereby when there is a tension on the clip the lever may not 60 swing backward to a released position. The limiting means mentioned comprises the ears or projections 18 on the clip arm 29 which act in conjunction with lateral extensions 37 on the inner edges of the lever arms 32 and 33 as shown 65 in Figs. 1 and 5.

Thus, as shown in Figs. 1 and 2, the extensions 37 of the lever are in engagement with the ears 18 of the clip body whereby when the lever has 70 been swung backward to a position substantially in the plane of the body of the clip fur-

ther rearward movement of the lever relative to the body is prevented, it being understood that at such time the cam 35 has entered into the notch or depression 25.

Extensions 37 on the lever arms also serve to 5 prevent excessive forward swinging movement of the lever relative to the body 10. The lower portion of the arm 28 of the body is somewhat wider than the upper portion thereof as clearly shown in Fig. 1 whereby on forward swinging 10 movement of the lever relative to the body the lower ends or shoulders 38 of extensions 37 of the lever arms will engage the forward face of the lower portion of the clip arm 28 and prevent excessive movement of the lever such as might 15 result in separation of the lever and clip body.

Attention is directed to the fact that when the clip is open the arm 29 extends across the inner open sides of the hook-like ears 17 carried by the arm 28 and pressure caused by 20 resiliency of the body member retains the lever in these ears 17. Therefore the arm 29 serves to prevent separation of the lever from the clip body. When the clip jaws are closed the leverage and tension on the parts serves to prevent 25 any casual separation of such parts. The length and width of the jaws 30 and 31 is such, relatively, that the jaw 31 may move into the jaw 30 when the jaws are squeezed together as shown in Fig. 13 for assembly or disassembly.

With this combination and arrangement the parts can be easily assembled but they are effectively held against separation by the shape of the hooks, and also by cooperation therewith of the resilient action of the body member.

Having thus set forth the nature of my invention, what I claim is:

1. In a clip of the class described, a body comprising a pair of arms connected at one end and having their other ends providing normally open 40 gripping jaws adapted to be forced closed, a pair of ears on one of said arms and extending therefrom across the edges of the other arm, said ears including in their lower edges similar hook-shaped portions the open sides of which 45 are toward the arms, a lever including portions pivotally mounted by said hook-shaped ear portions, and said other arm of the body extending across the open sides of and closing said hook-shaped portions when said jaws are open whereby 50 to prevent casual separation of the body and lever.

2. In a device of the class described, a one-piece clip body comprising a pair of integrally connected arms yieldable toward each other and 55 provided with gripping jaws at their free ends, one of said arms having ears on its opposite edges intermediate its length and extending toward the other arm, a lever, means pivotally mounting the lever between and within said ears, 60 said lever including spaced side arms and a connecting bar between the outer ends of said arms for attachment to a strap, a connecting bar between the other ends of the arms having a laterally extending cam means to engage the outer 65 wall of the other arm to press the jaws together as the lever is swung to the plane of the body and to permit the jaws to separate as the lever is swung forwardly to a position extending transversely of the body, and projections on the edges 70 of the second arm projecting inwardly into the path of the arms of the lever to prevent movement of the latter rearwardly over the body.

3. In a clip of the class described, a one-piece body comprising a pair of arms connected at one 75

end and having their other ends providing normally separated gripping jaws adapted to be forced toward each other to grip a garment, a pair of ears on the side edges of one of the arms 5 and extending across the edges of the other arm, said ears comprising similarly shaped hooked portions in their lower edges the open sides of which are toward the arms and directed laterally substantially in the plane thereof, a lever 10 including spaced side arms connected at their outer ends by a bar for connection to a strap, a second connecting bar between the inner ends of the side arms and adapted to enter said hooks to pivot the lever on the body, said second bar including a laterally extending cam means between the ears to engage the outer wall of the second body arm to press the arms together when swung into the plane of the body, and said cam means being located to permit insertion and removal of its lever bar through the open sides of the hooks when the arms of the body are pressed together and said connecting bar is substantially parallel with the plane of the body.

LEE OLIVER.
